UNITED STATES PATENT OFFICE.

CLARK T. HENDERSON, OF MILWAUKEE, WISCONSIN, ASSIGNOR TO THE CUTLER-HAMMER MFG. CO., OF MILWAUKEE, WISCONSIN, A CORPORATION OF WISCONSIN.

LIFTING-MAGNET CONTROLLER.

1,126,762.

Specification of Letters Patent.

Patented Feb. 2, 1915.

Application filed April 29, 1912. Serial No. 693,844.

To all whom it may concern:

Be it known that I, CLARK T. HENDERSON, a citizen of the United States, residing at Milwaukee, in the county of Milwaukee and State of Wisconsin, have invented new and useful Improvements in Lifting-Magnet Controllers, of which the following is a full, clear, concise, and exact description, reference being had to the accompanying drawing, forming a part of this specification.

My invention relates to improvements in circuit controllers.

It is particularly applicable to controllers for electro-responsive lifting magnets, but may be used in other relations.

It is one object of my invention to provide a controller for causing a lifting magnet to quickly release and drop its load when desired.

A further object of my invention is to provide a controller for establishing a back discharge path for the magnet winding upon interruption of its circuit to reduce the arcing at the circuit breaking points.

A still further object of my invention is to provide means for insuring the controller against such operations as might cause injury thereto or to the controlled device.

My invention has various other objects and advantages which will be hereinafter clearly and fully set forth.

For the purpose of disclosing the nature and characteristic features of my invention, I shall describe the embodiment thereof illustrated in the accompanying drawings. It should be understood, however, that my invention is not limited to the specific embodiment thereof chosen for the purpose of illustration.

In the accompanying drawings, Figure 1 is a front elevation of the controller, a portion of the inclosing casing removed and with certain parts shown in section. Fig. 2 is a top plan view of Fig. 1. Fig. 3 is a side elevation of the upper portion of Fig. 1. Fig. 4 is a sectional view taken on line 4-4 Fig. 1, and Fig. 5 is a sectional view taken on line 5-5 Fig. 1. Fig. 6 is a combined schematic and diagrammatic view of the controller and one form of circuit connections adapting the same to lifting magnet service.

The various parts of the controller shown

are mounted within a casing. This casing is provided with a back 1 and bottom 2 55 preferably formed integrally and of cast iron and with a top 3 preferably formed of cast iron and secured to the back 1 by any suitable means. This section of the casing is provided with suitable supporting lugs or 60 ears 4. The remaining sides of the casing are preferably formed of a sheet metal plate 5 adapted to be secured to the back of the casing by the usual devices 6.

Secured to the back 1 of the casing and 65 extending substantially the entire length thereof is an insulating switch supporting panel 9. Mounted upon this panel and extending transversely thereof are four switches, 10—11—12 and 13. These switches 70 are all of the same construction and accordingly a description of one will suffice for all.

Referring to Fig. 5, each switch comprises an arm 14 fulcrumed on a pin 15 carried by a bifurcated bracket 16 secured to the insulating panel 9. The switch arm 14 carries a main contact plate 17 adapted to engage with a stationary laminated brush 18. The brush 18 is secured to a holder 19 preferably set into the insulating panel 9 and secured 80 thereto in any preferred manner. The holder 19 has an extension 20 carrying a carbon contact 21. The carbon contact 21 is adapted to be engaged by an arcing contact 22 on the switch arm 14. The arcing 85 contact 22 is preferably mounted upon the extremity of a spring 23 secured to the arm 14 by suitable means such as a bolt 24 and screw 25. Confined between the spring arm 23 and arm 14 is a flexible conductor 26 90 which extends around the pivot 15 to a binding post 27 on the bracket 16. This provides an electrical connection between the bracket 16 and both contacts of the switch arm. The bracket 16 is provided with a 95 suitable terminal post 28. Both the main contact brush 18 and the carbon block 21 directly engage the contact holder 19 which is of conducting material and provided with a suitable terminal post 29. The contacts 10

are so disposed that upon inward movement of the arm 14 contact is first made between the arcing contacts and then between the main contact 17 and brush 18. Upon outward movement of the arm contact is first 10 broken between main contact 17 and brush

18 and then between the arcing contacts. The arm 14 is biased outwardly by a spring 30 set into the insulating base and bearing against said arm.

- 5 The switches are preferably provided with individual blowout devices and are so illustrated. These blowout devices are all of the same construction. As best illustrated in Figs. 3 and 5, each of these blowout devices 10 comprises an electromagnet 32 supported between the extremities of two magnetic plates 33 and 34 secured at their inner ends by suitable means such as bolts 35 to the insulating panel 5. The supporting plates 33 and 34 form pole pieces for the magnet 32 and are disposed on opposite sides of the arcing contacts. An insulating chute or barrier 36 is provided between each pair of plates 33 and 34 for the well-known purpose. 15 These chutes or barriers may be conveniently secured in place by means of bolts 37 passing through the same and through said plates.

- One terminal of each of the blowout devices 20 is adapted to be connected to the terminal post 29 of the stationary contact support while its opposite terminal is adapted to be connected to one of the terminal posts 38 provided upon the supporting panel 5. 25 The terminal posts 38 are adapted to be connected to outside circuits. Thus, upon closure of each switch a circuit is established from the binding post 28 through the switch arm and stationary contacts thence through 30 the blowout magnet to terminal 38.

- The switches 10-11-12 and 13 are 35 adapted to be operated by revolvable cams 40-41-42 and 43 respectively, mounted upon a shaft 44 extending longitudinally 40 through the casing. The shaft 44 is revolvably mounted in suitable bearings 45 provided in the top and bottom of the casing and is provided with a suitable operating handle 46.

- 45 Each of the cams preferably comprises an insulating disk secured to a suitable support 47 fixed to the shaft by suitable means such as a pin 48. The cams engage rollers 49 suitably mounted on the switch arms 14. 50 The cams are so constructed and so arranged upon the shaft 44 that when the shaft is in normal position the switches 10 and 11 will be closed and the switches 12 and 13 opened. When the shaft is revolved to the right, 55 switch 11 is opened and switch 12 closed. When the shaft is revolved to the left the switch 10 is opened and the switch 13 is closed. Further, the cams are so designed that when the shaft is revolved to the right, 60 the switch 12 will be closed before the switch 11 is opened and upon return movement the switch 11 will be closed before the switch 12 is opened. Likewise when the shaft is revolved to the left, the switch 13 65 will be closed before the switch 10 is opened

and upon return movement the switch 10 will be closed before the switch 13 is opened. The purpose of this sequence of operation will later be explained.

As will be later more fully explained, 70 when the device is used for controlling an electro-responsive lifting magnet the switches 10 and 11 when closed establish a back discharge circuit for the magnet winding. When the shaft is revolved to the 75 right, the opening of the switch 11 breaks the back discharge circuit while the closure of switch 12 connects the magnet to a power circuit. When the shaft is revolved to the left to close switch 13 and open switch 10, 80 the back discharge circuit is opened and the magnet connected to the supply circuit but in such a manner as to reverse the polarity. The purpose of reversing the polarity of the magnet is to cause it to repel its load thereby insuring a quick release or dropping thereof.

In practice it is desirable to only maintain the connections for reversing the polarity of the magnet for a moment. Otherwise the 90 magnet might drop its load and then immediately pick up the same. I, accordingly, prefer to bias the shaft from release or dropping position to off position so that the controller will remain in dropping position 95 only so long as the operator holds it in such position. There is no occasion for biasing the controller from lifting position to off position. In fact, such a provision might prove dangerous. In practice it is very 100 much preferred to positively insure the retention of the controller in lifting position until it is positively moved away from such position. I, accordingly, desire to provide means to this end. Still further, I desire 105 to provide means for positively limiting the movement of the controller from dropping position to off position to prevent the same from moving too far and unintentionally establishing lifting connection or bringing the contacts for establishing lifting connections into such positions that arcing would result. The controller shown is provided with means for accomplishing all 110 these results and I shall now describe said 115 means.

On the upper end of the shaft 44 I have provided a disk 50 which may be secured to said shaft in any preferred manner. On this disk is provided a pin 51 with which 120 engages one extremity of a spring 52 coiled around the shaft 44 and having its opposite end secured in the bearing 45 of said shaft. This spring is so coiled and disposed as to bias the shaft in a counter-clockwise direction, or in other words, from dropping position to off position. It is placed under tension as the controller is moved from off position toward dropping position. Movement 125 of the controller from off to lifting position 130

does not affect the spring. A lug 53 projecting downwardly from the top of the casing coöperates with shoulders 54 and 55 provided on the disk 50, to limit the rotation of the shaft in both directions from off position. It stops the shaft in lifting position and dropping position.

5 A spring pressed lever 56 carrying a roller 57 coöperates with a notched section of the disk to releasably lock the shaft in normal position and in lifting position. The lever 56 is fulcrumed upon a pin 58 projecting downwardly from the top of the casing and is yieldingly held in engagement with the 15 notched periphery of the disk by a tension device. This tension device includes a rod 59 suitably secured to the back of the casing and projecting between the bifurcations of a tail piece 60 of the lever 56. The rod 59 carries a helical spring 61 confined between a washer 62 bearing against the tail piece 60 of the lever 56 and a washer 63 on said rod retained in place by nuts 64. The spring 61 is of the expansion type.

25 The disk 50 is provided with a notch 65 into which the roller 57 of the lever 56 is adapted to enter when the controller is in off position and with a notch 66 into which the roller is adapted to enter when the controller is in lifting position. Thus the controller is insured against accidental movement from either its off position or its lifting position.

35 While the entry of the roller 57 into the notch 65 would tend to stop the controller in off position when returned to such position by the spring 52 it might under some conditions fail to so stop the controller. I accordingly prefer to provide a more positive stop which I shall now describe.

40 The operating handle of the controller instead of being rigidly fixed to the shaft is fulcrumed upon a horizontal pin 68 supported by a device 69 fixed to the shaft by 45 means of a pin 70. This permits of a vertical movement of the handle. The stop device coöperates with this handle. It comprises a member 71 secured as by means of bolts 72 to the top of the casing. The member 71 is recessed to receive the shank of the handle and to permit movement thereof from one extreme position to the other. The recessed portion of the member 71 is however, so formed as to require a vertical 55 movement of the handle in its travel from one extreme position to the other.

55 On one side of the central position of the handle, the member 71 is provided with a cam member 73 which raises the handle as 60 it is moved from its central position to its extreme left hand position. On the opposite side of the central position of the handle the member 71 is provided with a stop member 76 directly in the path of the shank 65 of the handle when in its elevated position.

To clear this stop the handle must be moved downwardly and in practice I prefer to provide only a small clearance between the handle shank and the stop 76 to necessitate downward movement of the handle to its 70 full extent to free the same from said stop. Also in practice I prefer to provide the stop 76 with a cushioning spring 77 for taking the impact of the handle.

In operation the handle is free to move 75 either from its central position or from its extreme right hand position to its extreme left hand position without interruption. Assume now that the handle is in its extreme left hand position and is released by 80 the operator. The return spring will then move the shaft and handle back toward the central "off" position and in so doing will drive the shank on the handle against the stop 76. This arrests the movement of the 85 handle in the central "off" position. The shaft is at this time relieved of the tension of the return spring. Accordingly the shaft will come to rest and the handle will drop to the position shown in Fig. 1, in which 90 position it is free to be moved in either direction. The stop 76 thus insures the shaft and handle against accidental movement beyond the central "off" position, but without in any wise interfering with the 95 manual operation thereof.

Referring now to Fig. 6 one application of the controller will be described. In this figure the controller is shown schematically. It controls the circuits of an electro-responsive lifting magnet 80 also schematically illustrated. The controller serves to establish the following circuit connections for the magnet winding. The controller is shown in "off" position in which the switches 100 10 and 11 are closed. The switches 10—11 complete a closed loop across the terminals of the magnet winding. This circuit may be traced from the left hand terminal of the magnet winding by conductor 81 through 105 the switch 10, by conductor 82 through the switch 11, by conductor 83 through a resistance R to the opposite terminal of the magnet winding. This circuit provides what is known in the art as a back-discharge 110 path for the winding to prevent excessive arcing at the switch contacts when the magnet is disconnected from the supply circuit. Assume now that the controller be moved to its extreme right hand or lifting position, 115 the switch 11 will be opened and the switch 12 closed. This connects the magnet winding to the supply circuit L—L'. The circuit of the magnet winding may now be traced from line L to conductor 82 through 120 switch 10 by conductor 81 through the magnet winding by conductors 80 and 84 through the switch 12 to line L'. The magnet is thus energized for lifting. Return of the controller to the central "off" position 125 130

- causes the switch 11 to first close thereby re-establishing the back-discharge circuit and then causing the switch 12 to open to disconnect the magnet winding from circuit.
- 5 This deenergizes the magnet. In some cases the residual magnetism is sufficient to cause the load to stick to the magnet after circuit is opened, thereby rendering the discharge of the load uncertain. If there is any tendency of the load to stick it can be readily overcome by continuing the movement of the controller to its extreme left hand position. This results in opening the switch 10 and closing the switch 13. Thereupon the 10 magnet winding is again connected to the supply circuit but in such a manner that its polarity is reversed. This will be obvious from tracing the circuit of the magnet winding which now extends from line L to conductor 82 through switch 11 by conductor 83 through resistance R, by conductor 84 through the magnet winding by conductor 85 through resistance R', thence through switch 13 to line L'. This circuit it will be 15 observed causes the current to flow through the magnet winding in an opposite direction to that previously described and accordingly causes a reversal of the polarity of the magnet winding causing it to quickly drop 20 its load. For this purpose only a comparatively small current is required and hence the inclusion of the resistances R and R'. In fact a small current for reversal is much preferred as the magnet would immediately 25 pick up its load after dropping the same if supplied with a full amount of current.
- What I claim as new and desire to secure by Letters Patent is as follows:—
1. A controller having a plurality of 40 switches operable to connect a translating device to a supply circuit for causing a flow of current therethrough in either direction and further operable to connect the translating device in a closed loop, and means insuring the establishment of said closed loop prior to disconnection of the translating device from circuit.
  2. A controller provided with a plurality of 45 switches operable to connect a translating device to a supply circuit to cause a flow of current therethrough in either direction and further operable to connect the translating device in a closed loop, and a common operating member for all of said 50 switches insuring the establishment of said closed loop prior to disconnection of the translating device from circuit.
  3. A controller comprising a plurality of 55 switches operable to connect a translating device to a supply circuit and to reverse the connections between the translating device and the supply circuit, and further operable to connect the translating device in a closed 60 circuit, and a single device for mechanically operating said switches to establish all of 65

said connections and to insure the establishment of said closed loop prior to disconnection of the translating device from circuit.

4. A controller comprising a plurality of 70 switches operable to connect a translating device to a supply circuit and to reverse the connections between the translating device and the supply circuit, to reverse the polarity of the former, and further operable to connect the translating device in a closed 75 circuit, and a single device for mechanically operating said switches to establish all of 80 said connections and to insure the establishment of said closed loop prior to disconnection of the translating device from circuit, 85 said device being movable in opposite directions from an intermediate position to connect the translating device in circuit and control the direction of flow of current therethrough, and when in said intermediate position to cause the establishment of 90 said closed loop.

5. In combination, a lifting magnet and 95 means operable to connect the magnet winding to a supply circuit, to reverse the polarity of the magnet winding and to connect the magnet winding in a closed loop.

6. In combination, a lifting magnet, 100 means operable to connect the magnet winding to a supply circuit, to reverse the polarity thereof and to connect the magnet winding in a closed loop, and means cooperating with said former means to insure the establishment of said closed loop prior to disconnection of the magnet winding from circuit.

7. In combination, a lifting magnet and 105 a plurality of switches, certain of said switches when closed connecting the magnet winding to the supply circuit, certain of 110 said switches when closed reversing the polarity of the magnet winding, and certain of said switches when closed establishing a closed loop including the magnet winding.

8. In combination, a lifting magnet, a 115 plurality of switches, certain of said switches when closed connecting the magnet winding to the supply circuit, certain of said switches when closed reversing the polarity of the magnet winding, and certain of said switches when closed establishing a closed loop including the magnet winding, 120 and a common operating member for all of said switches insuring the establishment of said closed loop prior to disconnection of the magnet winding from circuit.

9. In combination, a lifting magnet, a 125 plurality of switches, certain of said switches when closed connecting the magnet winding to the supply circuit, certain of said switches when closed reversing the polarity of the magnet winding, and certain of said switches when closed establishing a closed loop including the magnet winding, and a common operating member for all of 130 said switches insuring the establishment of

said closed loop prior to disconnection of the magnet winding from circuit, said member when moved to reverse the polarity of the magnet winding, tending to return to a 5 position to disconnect the magnet winding from circuit.

10. In a circuit controller in combination, four switches, and a common operating member therefor having three positions in 10 each of which it closes a pair of switches and allows another pair to open, said operating member always insuring closure of a certain pair of said switches prior to the opening of either one of the other two 15 switches.

11. In a controller in combination, four switches, two of said switches when closed being adapted to connect a translating device to a supply circuit, two of said switches 20 when closed connecting the translating device to the supply circuit but reversing the connections between the same and two of said switches when closed connecting the translating device in a closed loop, and a common operating member for said switches 25 movable to close the same in pairs to establish all of the aforesaid connections.

12. In a controller in combination, four switches, two of said switches when closed 30 being adapted to connect the translating device to a supply circuit, two of said switches when closed connecting the translating device to the supply circuit but reversing the connections between the same 35 and two of said switches when closed connecting the translating device in a closed loop, and a common operating member for said switches movable to close the same in pairs to establish all of the aforesaid connections, 40 said member insuring closure of the last mentioned pair of switches prior to the opening of either of the remaining two switches.

13. In a controller in combination, four switches, two of the same when closed being 45 adapted to connect a translating device to a supply circuit, two of the same when closed being adapted to connect the translating device to the supply circuit to reverse the polarity of the translating device, and two of the same when closed connecting the translating device in a closed loop, and a common operating member for all of said switches 50 adapted when in initial position to close the last two mentioned switches, when moved in one direction from normal position to close the first mentioned pair of switches, and when moved in the opposite direction from 55 normal position to close the second mentioned pair of switches.

14. In a controller in combination, four switches, two of the same when closed being 60 adapted to connect a translating device to a supply circuit, two of the same when closed being adapted to connect the trans-

lating device to the supply circuit to reverse the polarity of the translating device, and two of the same when closed connecting the translating device in a closed loop, and a common operating member for all of said 70 switches adapted when in initial position to close the last two mentioned switches, when moved in one direction from normal position to close the first mentioned pair of switches and when moved in the opposite 75 direction from normal position to close the second mentioned pair of switches, said member operating said switches through cams, and said cams being so designed as to insure closure of the third mentioned pair 80 of switches prior to the opening of either of the other two switches.

15. In combination, a switch controlling member movable between predetermined points, means biasing said member from 85 one of said points to an intermediate position, and means for positively checking the operation of said member at said intermediate position when said member is moved by said biasing means, said member when 90 brought to rest at said intermediate position being automatically freed for continued operation.

16. In combination, a switch controlling member movable between predetermined 95 points and biased from one of said points to an intermediate point, and means coöperating with said member to permit uninterrupted manual operation of said member from one extreme point to the other, but 100 positively stopping said member at said intermediate position upon automatic operation thereof.

17. In combination, a switch controlling member movable between predetermined 105 points and a device associated therewith permitting free movement of said member in one direction from one of said points to the other, but having a portion adapted to block the reverse movement of said member 110 at an intermediate point unless said member is adjusted during its movement to clear said portion.

18. In combination, a lifting magnet, means for connecting the magnet winding 115 to a supply circuit to obtain a flow of current therethrough in either direction, means for establishing a closed loop across the terminals of said winding prior to disconnection thereof from circuit, and a resistance 120 for said closed loop, said first mentioned means connecting said resistance in series with the magnet winding under predetermined conditions.

19. In combination, a lifting magnet, 125 means for connecting the magnet winding to a supply circuit to obtain a flow of current therethrough in either direction, means for establishing a closed loop across the terminals of said winding prior to disconnec- 130

tion thereof from circuit, and two resistances, said first mentioned means connecting both resistances in series with the magnet winding under predetermined conditions and said second mentioned means connecting one of said resistances in said closed loop.

In witness whereof, I have hereunto subscribed my name in the presence of two witnesses.

CLARK T. HENDERSON.
